(57) **CLAIM**

The ornamental design for a cigar shaped smoking holder, as shown and described.

DESCRIPTION

FIG. 1 is side perspective view of a cigar shaped smoking holder in accordance with an embodiment of the present invention;

FIG. 2 is a rear elevation of the cigar shaped smoking holder of FIG. 1;

FIG. 3 is a front elevation of the cigar shaped smoking holder of FIG. 1;

FIG. 4 is a right-side elevation of the cigar shaped smoking holder of FIG. 1;

FIG. 5 is a left-side elevation of the cigar shaped smoking holder of FIG. 1;

FIG. 6 is a top plan view of the cigar shaped smoking holder of FIG. 1; and,

FIG. 7 is a bottom plan view of the cigar shaped smoking holder of FIG. 1.

The broken lines show portions of the cigar shaped smoking holder that form no part of the claimed design.
